CLAIM

The ornamental design for a speaker as shown and described.

DESCRIPTION

FIG. 1 is a front top perspective view of a speaker showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a partially enlarged view thereof, corresponding to the encircled portion 9 indicated in FIG. 1; and,

FIG. 10 is a partially enlarged view thereof, corresponding to the encircled portion 10 indicated in FIG. 2.

The evenly dashed broken lines depict portions of the speaker that form no part of the claimed design. The dot-dash broken lines of FIGS. 1, 2, 9, and 10 are included to show partially enlarged views only and form no part of the claimed design.
